UNITED STATES PATENT OFFICE.

WILLIAM N. BEACH, OF NEW YORK, N. Y.

FEEDER-HEAD FOR ROTARY TUBE-MILLS.

No. 879,435.

Specification of Letters Patent.

Patented Feb. 18, 1908.

Application filed October 12, 1906. Serial No. 338,556.

To all whom it may concern:

Be it known that I, WILLIAM N. BEACH, a citizen of the United States, residing at New York city, in the county of New York and 5 State of New York, have invented a new and useful Improvement in Feeder-Heads for Rotary Tube-Mills, of which the following is a specification.

This invention relates to rotary tube mills 10 of the type employed in grinding cement and similar materials, and has special reference to an improvement in feeding mills of that character.

The invention primarily has in view a simple, practical, and thoroughly efficient form 15 of feeder head designed for use in connection with that type of rotary tube mills embodying in its organization a rotary mill shell or tube partially filled with grinding pebbles 20 which, through the attrition caused by the tumbling action, serve to grind the fine material introduced.

A special object of the invention is to provide a feeder head comprising means for uniformly 25 distributing the material to be ground into the mill shell or tube at the most advantageous point for the starting of the grinding action, and also at such an angle as to cause the material to take up and follow the movement of the pebbles or balls in the mill.

With these and many other objects in view which will readily appear as the nature of the 30 invention is better understood, the same consists in the novel construction, combination, and arrangement of parts hereinafter more 35 fully described, illustrated and claimed.

A preferred embodiment of the invention is shown in the accompanying drawings, in which:

40 Figure 1 is a sectional view of the feeding end portion of a rotary tube mill equipped with the improved feeder head contemplated by the present invention. Fig. 2 is a side or face elevation of the feeder head.

45 Like references designate corresponding parts in the separate figures of the drawings.

In carrying the invention into effect no special changes are required in the construction of the usual parts of the ordinary type of 50 rotary tube mill which includes in its construction a rotary mill shell or tube designated in the drawings by the numeral 1, and designed to be partially filled with pebbles or balls tumbled about through the rotation of

the mill and thereby causing the grinding of 55 the fine material introduced therein.

The mill also includes as one of the elements thereof the main end head 2 constituting the main closure for one end of the mill shell or tube 1 and provided at the center 60 thereof with an inlet opening 3 receiving material which is primarily fed to the mill through the usual hollow trunnion or sleeve 4. These parts of the mill are the common and usual ones and the functions thereof are 65 well understood by those familiar with this art, but in connection with the present invention it is to be observed that the main mill end head 2 is of a dished formation in cross section and is provided with an inclined sec- 70 tion 5 adjoining the end of the mill shell or tube and coöperating with the interior feeder head or diaphragm 6 which constitutes the distinctive and essential feature of the invention.

The interior feeder head or diaphragm 6 is 75 arranged at the inner side of the main end head 2 and is held in spaced relation to said head to provide an intervening feed chamber 7 in direct communication with the central inlet opening 3 for the material. In its structural formation the feeder head or diaphragm 6 substantially consists of a circular baffle plate of less diameter than the interior of the shell or tube 1 and having an imperforate body portion which is preferably reinforced 80 by means of a plurality of integral reinforce webs or ribs 8 provided upon the inner side of the plate body. The outer side of the plate body constituting the feeder diaphragm or head 6 is formed with a main central con- 85 icial portion 9 concentrically disposed with reference to the central inlet opening of the mill end head and serving as a deflecting and distributing surface over which the material is uniformly spread in radial directions 90 toward the periphery of the head. The peripheral edge portion of the baffle plate constituting the feeder head or diaphragm, designated by the number 10, is set at an inclination in parallelism with the flat in- 95 clined section 5 of the main end head, and this peripheral edge portion 10 is provided thereon with a thickened laterally offset distributing ring 11, which abuts directly against the inner side of the section 5 of the 100 end head 1 and acts as the spacing block or member which holds the feeder head or diaphragm in spaced relation to the end

105

head, to provide the intervening feed chamber 7. The two heads are held in this relative position through the medium of any suitable fastenings or fastening connections, 5 but a convenient and practical expedient is shown in the accompanying drawings and resides in the employment of a circular series of fastening bolts 12 extending across the feed chamber space 7 and secured in both the end head 5 and the feeder head 6.

A special feature of importance in the present invention is that of having the laterally offset distributing ring 11 pierced by a continuous circular series of obliquely disposed feeding ports or holes 13 which are preferably of a rectangular form in cross section as may be plainly seen from both of the figures of the drawings. These feeding ports or holes extend in a closely arranged 15 series and entirely about the circle of the offset distributing ring 11, and pierce said ring in a plane parallel with the inclined section 5 of the end head 2 and the peripheral edge portion of the feeder head 6 as shown in 20 the upper part of Fig. 1 of the drawings, and it will be further observed that the said ports or holes 13 have their inner ends in communication with the feed chamber 7 between the two heads, and their outer ends 25 in communication with the interior of the mill shell or tube 1 contiguous to the inner wall of the latter. Furthermore, it is to be noted that the said ports or holes 13, in addition to their parallel relation to the elements 5 and 10, are disposed obliquely to the 30 radii of the feeder head. This oblique disposition of the feeding ports or holes 13 provides for what may be termed a tangential feeding of material into the mill shell or tube, 35 thereby causing the same to immediately 40

take up and follow the rotation of the latter and the tumbling action of the grinding pebbles or balls.

I claim:

1. The combination with the mill shell, and 15 the end head having a central inlet opening, of an interior feeder head arranged at the inner side of the end head in spaced relation to the latter and provided with a distributing ring having therein a continuous series of 50 obliquely disposed feeding ports or holes.

2. The combination of the mill shell, and 55 the end head having an inclined portion and a central inlet opening, an interior feeder head arranged at the inner side of the end head in spaced relation thereto and provided at its peripheral edge portion with a laterally offset distributing ring abutting against the inclined portion of said end head and provided therein with a continuous series of 60 obliquely disposed feeding ports or holes.

3. The combination with the mill shell, and 65 the end head provided with an inlet opening, of an interior feeder head secured to the inside of said end head in spaced relation thereto, said feeder being provided with a central conical portion and a lateral offset peripheral distributing ring in which are formed a series of feed ports or holes in communication with the feed chamber between the two heads and 70 arranged oblique to the radii of the feeder head.

In testimony whereof, WILLIAM N. BEACH has signed his name to this specification in the presence of two subscribing witnesses. 75 this 29th day of September, 1906.

WM. N. BEACH.
